(57) **CLAIM**

The ornamental design for a mini laser level, as shown and described.

DESCRIPTION

FIG. 1 is an isometric view showing the mini laser level of my new design;

FIG. 2 is a side elevational view of the mini laser level;
FIG. 3 is a side elevational view of the mini laser level of the end opposite the end shown in FIG. 2;

FIG. 4 is an end elevational view of the mini laser level;
FIG. 5 is an end elevational view of the mini laser level of the end opposite the end shown in FIG. 4;

FIG. 6 is a top plan view of the mini laser level; and,
FIG. 7 is a bottom plan view of the mini laser level.

The broken line showing of the level bubbles and knobs of the mini laser level is included for the purpose of illustrating portions of the article and forms no part of the claimed design.
